(No Model.)

A. A. CAILLE.
CASH CARRIER.

No. 427,396.

Patented May 6, 1890.

UNITED STATES PATENT OFFICE.

ARTHUR A. CAILLE, OF EAST SAGINAW, MICHIGAN, ASSIGNOR TO THE
CAILLE CASH CARRIER COMPANY, OF SAME PLACE.

CASH-CARRIER.

SPECIFICATION forming part of Letters Patent No. 427,396, dated May 6, 1890.

Application filed March 21, 1888. Serial No. 268,041. (No model.)

To all whom it may concern:

Be it known that I, ARTHUR A. CAILLE, a citizen of the United States, residing in the city of East Saginaw, county of Saginaw, and 5 State of Michigan, have invented certain new and useful Improvements in Cash-Carriers; and I hereby declare the following to be a full, clear, and exact description of my invention, and one that will enable others skilled 10 in the art to which it appertains to make and use the same, reference being had to the accompanying drawings, and to the letters of of reference marked thereon, which form a part of this specification.

15 My invention has for its object the provision of an effective and simple means for projecting a car over a taut wire by means of manual force alone.

In the drawings, Figure 1 is a side elevation 20 of my improved cash-carrier apparatus. Fig. 2 is a sectional view of the same, with the arm thrown out. Fig. 3 is a detail view of the catch-lever.

25 In carrying out my invention, A represents a hollow standard descending from the ceiling.

B is a taut wire, and C a car adapted to travel on the wire.

30 a are arms rigidly engaged to the standard and extending out to a single point, thus forming a rigid bracket.

D is a propelling-arm in the form of a bell-crank, and is fulcrumed at the outer ends of the arms a. One arm d extends toward the 35 standard, and enters the latter through the slot a', while the other arm d' descends to a point adjacent to the wire, where it is slotted, as at d', and embraces the propelling-block E. This propelling-block E loosely 40 braces the wire and slides thereon, and is provided with the projection e on its under side to engage the car.

F is a small lever pivoted to the lower end 45 of the arm d' and adapted to catch and hold the car on its entering the station. The lever is beveled at its outer end f, to enable it to readily engage itself with the beveled projection c on the bed-plate of the car. By providing the shoulder f' the lever is prevented

from dropping below a position at right angles to the arm, and is held to such a position by the spring f'.

G are small leaf-springs engaged to the standard below the wire, and are adapted to lessen the shock of the incoming car by bearing on the projection c' on the bed-plate thereof.

H is the cord or wire whereby the arm is actuated. It is attached to the arm d, and extends down through the standard to a point 60 below and within easy grasp of the operator, where it is provided with the handle H'.

J is a spring adapted to return the propelling-arm to its normal position after the car has been projected.

The operation will now be understood: The propelling-arm remains in the position shown in Fig. 1, with the car engaged by the small lever F. The operator grasps the handle H' and gives it a quick jerk. This draws down 70 the inner end of the arm d'. This causes the propelling-block to project the car rapidly over the wire, the car being released from engagement with the lever F, from the fact that the end of the latter is raised by the arm as 75 it is thrown forward. After the car has been projected the spring J returns the arm to its normal position. Of course the location of the spring might be changed, and it be located in any convenient position, its office 80 being simply to return the arm to its normal position.

Of course I do limit myself to a spiral spring, as shown, since a rubber band might serve the purpose equally well. Neither do I limit myself to a cord or wire for actuating the arm, since a rod engaged to the arm might be used, and would of course be contemplated by me. By making the end of the arm d' to loosely straddle the propelling-block, and by providing the latter with shoulders e' on its ends, the block is given a slight play, and yet securely held by the arm. This is advantageous when the incoming car strikes the block, since it gives it a chance to yield somewhat.

What I claim is—

1. In a cash-carrier apparatus, the combination, with the standard, the wire, and car,

of a pivoted propelling-arm carrying a catch for engagement with the car, a cord for actuating said arm to forwardly propel the car, and means for retracting the arm to its normal position, substantially as described.

2. In a cash-carrier apparatus, the combination, with the standard, the wire, and the car, of a pivoted propelling-arm carrying a catch for engagement with the car, a cord for actuating said arm, and a spring for retract-

ing the arm to its normal position, substantially as described.

In testimony that I claim the above as my invention I have hereunto set my hand, at Detroit, Michigan, this 24th day of February, 1888.

ARTHUR A. CAILLE.

In presence of—

E. W. ABBOTT,
I. W. SQUIRE.
